UNITED STATES PATENT OFFICE.

BENNETT R. LEWIS AND JOHN SCHWARTZ, OF RHINELANDER, WISCONSIN.

PUMP-GOVERNOR.

SPECIFICATION forming part of Letters Patent No. 628,101, dated July 4, 1899.

Application filed January 29, 1898. Serial No. 668,392. (No model.)

To all whom it may concern:

Be it known that we, BENNETT R. LEWIS and JOHN SCHWARTZ, of Rhinelander, in the county of Oneida and State of Wisconsin, have invented a new and useful Improvement 5 in Pump-Governors, of which the following is a description, reference being had to the accompanying drawings, which are a part of this specification.

Our invention has relation to improvements 10 in pump-governors. It relates more particularly to the class of governors which are connected to a pumping-engine and water-main and adapted for automatically controlling the 15 operation of the engine by the varying water-pressure, being more especially intended for use in connection with a water-supply system for a city, town, village, factory, or other large establishment or institution.

The primary object had in view is to provide 20 a construction whereby a uniform speed of the pump may be obtained notwithstanding the variations in the water-pressure, which is accomplished by admitting more steam to the pump as the water-pressure increases and, vice versa, by limiting the amount of steam to the pump as the water-pressure decreases, in contradistinction to constructions wherein the amount of steam admitted to the pump is 25 decreased as the water-pressure increases and, vice versa, the amount of steam admitted to the pump increased as the water-pressure is decreased.

With the above primary and other incidental objects in view the invention consists 30 of the devices and parts or their equivalents, as hereinafter more fully set forth.

In the accompanying drawings, Figure 1 is a vertical sectional view of one form of the 35 device, the mechanism for regulating the water-pressure against the piston 23 being omitted. Figs. 2, 3, and 4, respectively, are similar views of modified forms. Fig. 5 is a vertical sectional view of a form substantially 40 similar to the Fig. 1 form, but in which mechanism for regulating the water-pressure against the piston of the main water-cylinder is included. Fig. 6 is a cross-section through the water-valve mechanism of Fig. 5.

Referring particularly to the Fig. 1 form of construction, the numeral 7 indicates a valve-casing having an inlet-passage 8 for the ad-

mission of steam or other actuating medium into the casing and an outlet-passage 9 for the outflow of the actuating medium from 55 the valve-casing into the steam-cylinder of an ordinary form of pump. (Not shown.) The inner end of the inlet-passage, which extends into the valve-casing, is provided in its upper and lower portions with valve-openings 10 10', which are controlled, respectively, by valves 11 11', which valves are mounted on a common valve-stem 12. This valve-stem extends through the top of the valve-casing and advisably through a stuffing-box 13. Ex- 60 tending upwardly from the top of the valve-casing and preferably integral therewith is a frame 14. The back piece of this frame is provided with an elongated slot 15, in which slot a lever 16 is pivoted on a pivot-pin 17. 65 The long arm of this lever is provided medially with an elongated slot 18, and into this slot passes a pivot pin or stud 19 from the valve-stem. Mounted on the long arm of the lever between this pivot pin or stud and the 70 end of said long arm is a weight 20, which is provided with an upwardly-extending yoked portion through which the lever passes. A set-screw 21 extends through the upper end of the yoke and impinges against the lever, 75 so that the weight may be held in adjusted position on the lever at points closer to or farther from the pivot pin or stud 19. Secured to the face of the back piece of the frame is a water-cylinder 22, in which a pis- 80 ton 23 is adapted to reciprocate. The stem 24 of this piston passes downwardly through the lower end of the cylinder and has projecting from a medial point thereof a pin or stud 25, which extends into an elongated slot 85 26 in the end of the short arm of the lever 16. The lower end of the piston-stem 24 is guided in an eye formed at the outer end of a projecting arm 27. Extending into the top of the cylinder 22, above the piston 23, is a pipe 90 28, which leads from the reservoir or other suitable source of water-supply in the system.

In the operation of the Fig. 1 construction when an excess water-pressure occurs, the piston 23 will be caused to descend, and this 95 through the described connection will turn the lever 16 on its pivot 17, so as to throw the long arm of said lever upwardly. This upward throw will, through the valve-stem

12, raise the valves 11 11' away from their valve-seats. The lower the piston 22 is forced downwardly the higher the valves will be raised, and consequently more steam admitted. The steam thus admitted into the casing passes through the outlet-passage 9 and enters the steam-cylinder of the pump, so as to act on the piston therein and cause a reciprocation of the piston of the pump.

10 The weight is of course adjusted on the long arm of the lever, so as to counterbalance the water-pressure on the piston 23 after said piston has been moved downwardly a certain distance, thereby keeping the pump running

15 at a certain number of strokes in accordance with a certain degree of water-pressure. Of course when the water-pressure on the top of the piston 23 decreases the weight will cause the long arm of the lever to move downwardly,

20 and thereby depress the valve-stem 12 and raise the piston 23. The depression of the valve-stem 12 will cause the valves 11 11' to move toward their seats, thereby diminishing the area of the valve-openings, and consequently

25 limiting the amount of steam admitted to the steam-cylinder of the pump. It follows from the operation described that with increased water-pressure the amount of steam admitted to the pump is increased

30 and that with decreased water-pressure the amount of steam admitted to the pump is decreased. This is an improvement over existing constructions, in which the very reverse operation takes place—that is to say, in such

35 constructions with increased water-pressure the amount of steam admitted to the pump is decreased, and, vice versa, with decreased water-pressure the amount of steam admitted to the pump is increased. On this account

40 these existing systems are open to serious objections, which our invention overcomes. For instance, when there is decreased water-pressure of course the pressure of the water against the piston in the water-cylinder of

45 the pump is lessened, and inasmuch as in such existing systems the amount of steam admitted to the steam-cylinder of the pump at this time is increased, the pump is not only caused to reciprocate more rapidly by the increased steam-pressure, but also by the diminished resistance offered by the water, resulting frequently in the pump "running away," so to speak, and also resulting in an unnecessary expenditure and loss of steam.

50 In our device the moment the water-pressure is diminished there is consequently less resistance offered by the water against the piston in the water-cylinder of the pump, and it is at this time that less steam is required

55 to work the pump. We therefore diminish the steam-supply and effect a saving of steam when it is necessary only to use a small quantity, while, on the other hand, when the water-pressure is increased and there is a greater

60 resistance against the piston of the water-cylinder of the pump we admit more steam, thereby only utilizing an augmented quan-

65 tity of steam at the time when it is absolutely necessary that such increased quantity should be used. By this means the pump may be 70 made to run at a uniform rate of speed notwithstanding variations in the pressure of the water. By the employment of the weight on the lever the desired speed of the pump can be regulated. By moving the weight 75 nearer the pivot 18 said weight gives less resistance to the water-pressure, and consequently the valves are opened wider to admit more steam, and by moving the weight farther away from the pivot 18 said weight 80 offers more resistance to the water-pressure, and consequently the valves are not open so wide and less steam is admitted to the pump.

In order to prevent the valves from closing entirely, so as to shut off steam to the pump, 85 and, on the other hand, to prevent the valves from opening beyond a certain point, we mount on the valve-stem 12 adjustable collars 29 29'. Extending from the frame 14 is an arm 30, which is provided at its outer end 90 with an eye through which the valve-stem 12 passes. This eyed portion not only forms a guide for the valve-stem in its movement, but inasmuch as it is located between the two collars 29 29' it forms a contact with which 95 said collars come into engagement. As the stem moves downwardly it is obvious that the collar 29 will contact with the arm 30 and prevent the complete closing of the valves, and as said valve-stem moves upwardly the 100 collar 29' will contact with the arm 30, and thereby limit the extent to which the valves can be opened.

Referring now to the Fig. 2 form of construction, this shows a valve-casing 7^a, having an inlet-passage 8^a and an outlet-passage 9^a. In this casing but a single valve 11^a is employed, which regulates the outlet 9^a. Secured to or forming a part of the top of the valve-casing is a frame 14^a. To an intermediate cross-bar of this frame is pivoted medially a lever 31, provided at opposite ends with elongated slots 32 and 33, respectively. Into the slot 32 extends the pin or stud 18^a of the valve-stem 12^a. The upper end of the valve-stem passes through a bearing 34, formed in the top portion of the frame 14^a, and above and below this bearing are set the adjustable collars 29^a. The water-cylinder 22^a is mounted on the top piece of the frame 14^a, and the piston-stem 24^a of the piston 23^a is provided at its lower end with a projecting pin or stud 25^a. Pivoted to a cross-bar of the frame 14^a on a pivot-pin 35 is a lever 36, the short arm of said lever being provided medially with an 115 elongated slot 37, which is engaged by the projecting pin 25^a of the stem 24^a. The end of this short arm of the lever 36 is provided with a projecting pin or stud 38, which engages the elongated slot 33 of lever 31. The 120 long arm of lever 36 has mounted thereon adjustably a weight 20^a. This weight is provided with a yoke portion which is adapted to be engaged with any of a series of notches

in the upper edge of the lever, whereby the weight is held to adjusted position. In operation this form of device works substantially similar to the form shown in Fig. 1, although it involves a compound lever mechanism. It is obvious that as the piston 23^a moves downwardly it will act on the short arm of the lever 36, so as to throw the long arm of said lever upwardly against the action of the weight, and at the same time the arm of the lever 31 which is engaged by the short arm of the lever 36 is turned so as to throw the other arm of said lever 31 upwardly, and thereby raise the valve farther away from its seat in order to permit of an increased quantity of steam passing into the steam-cylinder of the pump. When the water-pressure decreases, it is obvious that a reverse operation will take place.

In the Fig. 3 construction a slightly-varied form of valve-casing is employed in which the valve-opening is closed on the up movement of the valve-stem instead of being opened, as in the preceding forms of construction. In this Fig. 3 modification also the valve-stem serves as the piston-stem for the piston in the water-cylinder. The valve-casing of Fig. 3 is indicated by 7^b, the valve by 11^b, the combined valve-stem and piston-stem by 12^b, the frame mounted above the valve-casing by 14^b, the water-cylinder by 22^b, the piston therein by 23^b, the pipe entering the cylinder by 28^b, and the lever by 16^b. The lever 16^b is pivoted intermediate of its ends to one of the side pieces of the frame 14^b, and the short arm of this lever is provided with an elongated slot which is engaged by the projecting pin or stud 18^b of the combined valve-stem and piston-stem. The long arm of the lever carries thereon the adjustable weight 20^b. The contact-collars on the valve-stem 12^b in this form of construction are indicated by the numerals 29^b 29^b.

In the operation of the Fig. 3 form of construction, when there is excess water-pressure the piston 23^b is caused to descend, and this forces the valve 11^b downwardly farther away from its seat, so as to open the valve-opening leading to the outlet-passage, and consequently admitting more steam to the steam-cylinder of the pump. When the water-pressure is decreased and the weight causes a turning of the lever 16^b, so as to throw its short arm upwardly, the valve is raised toward its seat, thereby diminishing the area of the valve-opening, and consequently decreasing the amount of steam passing to the pump.

In the Fig. 4 form of construction the valve-stem and piston-stem are also in one piece; but in this form water is introduced into the lower end of the water-cylinder, so as to cause any excess pressure to act against the under side of the piston in said cylinder. This causes an uplifting of the valve, so as to admit more steam to the pump. When the water-pressure decreases, the weight causes a tilting of the lever and a consequent down-

movement of the valve toward its seat. In this form it will be noticed that the lever is pivoted at its end to one of the side pieces of the frame and that the projecting stud or pin of the valve-stem enters an elongated slot at a point of the lever intermediate its ends instead of at the end of the lever, as in the Fig. 3 form. In this modification (illustrated in Fig. 4) the different parts are designated by the same numbers as the corresponding parts are designated in Fig. 3, excepting that said numbers are followed by the letter *c*.

In the form of construction illustrated in Fig. 5 of the drawings, which construction is adapted to be used in conjunction with any of the several forms of construction illustrated in the accompanying drawings, we designate the valve-casing by 7^d, the valve by 11^d, 85 the valve-stem by 12^d, the projecting pin or stud of said valve-stem by 18^d, the stop-collars on the valve-stems by 29^d 29^d, the frame by 14^d, the water-cylinder by 22^d, the piston therein by 23^d, the piston-stem by 24^d, the projecting pin or stud of said piston-stem by 25^d, the lever by 16^d, the adjustable weight thereon by 20^d, and the pipe leading to the water-cylinder by 28^d. The lever 16^d in this form of construction is arranged and operates substantially similar to the lever 16 of Fig. 1. In all the forms of construction illustrated mechanism is employed for controlling the strokes of the pump. In the Fig. 5 form, however, we show additional mechanism for controlling the amount of water-pressure. This mechanism, however, it will be obvious, is equally applicable to all the other forms of construction shown. To accomplish this, we provide a supplemental water-cylinder 39, 105 which is in communication with the pipe 28^d by means of a branch pipe 40. Within the cylinder 39 is a piston 41. The piston-stem 42 of this piston extends upwardly through the top of the cylinder 39 and has projecting 110 from the upper end thereof a pin or stud 43, which engages an elongated slot 44 in a lever 45. One end of this lever is pivoted to an arm 46, extending upwardly from the cylinder 39. This lever carries an adjustable 115 weight 47. Within the pipe 28^d is arranged a rotatable valve 48, (see Fig. 6,) which is provided with a straight passage 49 and with a diagonal passage 50, leading from the straight passage. The outer end of the valve-stem 51 120 has secured thereto a crank 52, and the outer end of this crank is connected to the lever 45 by means of a link 53. In the operation of this water-pressure-regulating mechanism if, for instance, the weight 47 is so positioned 125 on the lever 45 as to resist an upward pressure of, say, eighty pounds against the under side of the piston 41 the valve 48 will be in the position shown in Fig. 6—that is to say, with its straight passage 49 in line with the pipe 28^d and its diagonal passage 50 closed, so that free passage for the water is afforded to the cylinder 22^d. If now the pressure exceeds eighty pounds, then the piston 41 will

rise against the resistance of the weight 47 and cause an uplifting of the lever 45 and a consequent turning of the valve 48, so that the straight passage 49 will be closed against 5 the flow of the water through the pipe 28^d to cylinder 22^d, while the diagonal passage will be in line with a drip or discharge pipe 54. Pressure against the piston 23^d will then cease and the weight 20^d will cause a turning of the 10 lever 16^d and a consequent down movement of the valve-stem 12^d and an upward movement of the piston 23^d, which will force the water above said cylinder back through the pipe 28^d, thence through a portion of the 15 straight passage 49 into the diagonal passage 50 and out through the drip or discharge pipe 54. This drip or discharge pipe may be provided with a valve 55 to regulate the quantity of discharge. The downward movement 20 of the valve-stem 12^d will cause a closing of the valve 11^d to the extent permitted by the stop-collar 29^d, so as to almost entirely shut off the supply of steam, or where the stop-collars are dispensed with to cause an entire 25 shutting off of the steam. The operation described will of course cause a reduction in the water-pressure, and the piston 41 will then be caused to descend by the action of the weight 47, and it will continue to descend 30 until it reaches the position it before occupied, when, of course, the valve 48 will have been turned back to its original position to again admit water into the cylinder 22^d, thereby reestablishing the water-pressure to 35 the extent to which the weight 47 is adjusted.

In explanation of the particular adaptability of all the forms of our invention to use in connection with a city's waterworks it is to be stated that when water is being taken 40 from the system the water-pressure against the piston in the water end of the pump is necessarily decreased. In view of this decrease of the water-pressure it necessarily follows that it does not require as great a 45 steam-pressure to keep the pump running at a uniform speed or at the same speed as when water is not being used or when but a small quantity of water is being used. Hence it is that in our invention when the water is being used, and when therefore the water-pressure against the piston in the water end of the pump is thereby decreased, the quantity of steam admitted to the steam end of the pump is decreased, as at this time it is obvious that less steam-pressure is required to 55 preserve the uniform running of the pump, owing to the fact that there is less water-pressure against the piston in the water end of the pump. This decrease of the steam-pressure is automatically effected by means of the weight acting on the lever, and thereby actuating the valve-rod and causing the valve to limit the amount of steam admitted to the steam end of the pump. Now when the quantity of water being used is diminished of course the water-pressure against the piston in the water end of the pump is increased.

It is then necessary that the steam-pressure should be increased in order to counteract the increased water-pressure and preserve a uniform running of the pump. This is automatically effected by means of the mechanism already clearly described. It is a fact also to be noted that in a city's waterworks the steam end of the cylinder of the pump is 70 larger than the water end. It therefore follows that when water is being used not only is less steam required owing to the diminished pressure of the water, but also owing to the fact that the piston in the water end of 80 the cylinder of the pump is less in area than the piston in the steam end of the cylinder of the pump. In other systems now in general use when the water-pressure decreases the steam-pressure increases, and vice versa. 85 These systems are objectionable, owing to the fact that the increased steam-pressure frequently causes a running away of the pump and also a greater consumption of steam than is absolutely necessary.

While we have shown in all the several forms of our invention an adjustable weight for keeping the pump running at a certain number of strokes in accordance with a certain degree of water-pressure, yet we do not 90 wish to be understood as limiting ourselves thereto, as it is obvious that the same result could be obtained by spring-pressure on the lever, with means for adjusting or varying the extent of said spring-pressure.

What we claim as our invention is—

1. In a governor for pumps, the combination of a valve-casing provided with a suitable inlet-passage and an outlet-passage, the latter leading to the pump to be operated, a 105 valve within the casing, a cylinder within the circuit of the water system, a piston within the cylinder, a rod having one end extending into the valve-casing and connected to the valve therein, and having its opposite end 110 extending into the cylinder and connected to the piston therein, and a pivoted lever connected at one point to the rod, and also carrying thereon an adjustable weight, the construction adapted, as the water-pressure 115 against the piston increases, to move the valve farther away from its seat, to thereby admit an augmented quantity of steam to the pump, and, vice versa, when the water-pressure against the piston decreases, to cause the 120 valve to be moved closer to its seat, so as to admit a diminished quantity of steam to the pump.

2. In a governor for pumps, the combination, of a valve-casing provided with a suitable inlet-passage and with an outlet-passage, the latter leading to the pump to be operated, a valve within the casing adapted for controlling the pump-actuating medium, and provided with a projecting valve-stem, a main 125 cylinder, a valve-controlled water-pipe within the system of water-supply and leading to said cylinder, a piston within the cylinder, mechanism between the piston and the stem of the 130

valve for controlling said valve, an auxiliary cylinder also within the water-supply system, a piston within said auxiliary cylinder, and a connection between the piston of this auxiliary cylinder and the valve of the water-pipe, said connection adapted, after the water-pressure exceeds a certain given pressure, to cause the valve of the water-pipe to be operated so as to shut off the flow of water to the main cylinder, and after the water-pressure has fallen to the fixed pressure, to open the water-valve, and permit the water to again flow to the main cylinder.

3. In a governor for pumps, the combination, of a valve-casing provided with a suitable inlet-passage and with an outlet-passage, the latter leading to the pump to be operated, a valve within the casing for controlling the pump-actuating medium, said valve provided with a projecting stem, a main cylinder, a valve-controlled water-pipe within the water-supply system and leading to the main cylinder, a piston within said cylinder and provided with a projecting piston-stem, a lever connected to the piston-stem and to the valve-stem, said lever adapted to move the valve farther away from its seat to admit an augmented quantity of steam to the pump, when an excess water-pressure occurs, and to move said valve closer to its seat to admit a decreased quantity of steam to the pump, when the water-pressure is decreased, an auxiliary cylinder also within the water-supply system, a piston within said auxiliary cylinder, and a connection between said piston and the valve of the water-pipe, said connection adapted, after the water-pressure exceeds a certain given pressure, to cause the valve of the water-pipe to be operated so as to shut off the

flow of water to the main cylinder, and, after the water-pressure has fallen to the fixed pressure, to open the water-valve and thereby permit the water to again flow to the main cylinder.

4. In a governor for pumps, the combination of a valve-casing provided with a suitable inlet-passage and an outlet-passage, the latter leading to the pump to be operated, a valve for controlling the pump-actuating medium, said valve provided with a projecting stem, a main cylinder having a piston therein, a connection between said piston and the stem of the valve for the pump-actuating medium, a pipe within the water-supply system, said pipe leading to the main cylinder, a valve within said pipe adapted normally to admit the water to the main cylinder, an auxiliary cylinder also within the circuit of the water-supply system, a piston within said cylinder, said piston provided with a projecting stem, a pivoted lever connected to the piston-stem of the auxiliary cylinder, an adjustable weight on said lever, and a connection between the lever and the stem of the water-valve, whereby, when the water-pressure exceeds a certain fixed pressure, the valve will be operated so as to shut off the flow of water to the main cylinder, and when the pressure returns to its normal state, said valve is adapted to be operated so as to again permit the water to flow to the main cylinder.

In testimony whereof we affix our signatures in presence of two witnesses.
